PEER SMED, OF WOODHAVEN, NEW YORK, AND FREDERICK W. STARK, OF MERIDEN, CONNECTICUT, ASSIGNEES TO WALDORF-ASTORIA HOTEL CORPORATION, OF NEW YORK, N. Y., A CORPORATION OF NEW YORK

DESIGN FOR A DISH OR OTHER SIMILAR ARTICLE OF HOLLOW-WARE, CHINA, OR GLASS

Application filed March 23, 1931. Serial No. 39,220. Term of patent 14 years.

To all whom it may concern:

Be it known that we, PEER SMED, a subject of the King of Denmark, residing at Woodhaven, county of Queens, State of New York, and FREDERICK W. STARK, a citizen of the United States, residing at Meriden, county of New Haven, State of Connecticut, have invented a new, original and ornamental Design for a Dish or Other Similar Article of Hollow-ware, China, or Glass, of which the following is a specification, reference being had to the accompanying drawings, forming a part thereof.

Fig. 1 is a fragmentary view, of the ornamental border only, for the purpose of bringing out details of the design;

Fig. 2 is a top plan view of a dish embody-

ing our new design,—it being understood that the ornamentation is continued around the entire circumference, the edge of the dish being of conventional thickness and the bowl of conventional depth.

The ornamental design is here shown as applied to a dish for the purpose of illustration; but it is likewise applicable to napery or similar articles, and such use is within the purview of the invention.

We claim:

The ornamental design for a dish or other similar article of hollow-ware, china or glass, substantially as shown and described.

PEER SMED.

FREDERICK W. STARK.
